UNITED STATES PATENT OFFICE.

FRANK M. PIERCE AND WILLIAM BURGESS PIERCE, OF CHICAGO, ILLINOIS, ASSIGNEES
TO PIERCE WRAPPING MACHINE COMPANY, OF CHICAGO, ILLINOIS, A CORPORATION
OF ILLINOIS.

MACHINE FOR WRAPPING COMMERCIAL COILS OF WIRE.

1,158,405.

Specification of Letters Patent.

Patented Oct. 26, 1915.

Application filed May 21, 1909. Serial No. 497,528.

To all whom it may concern:

Be it known that we, FRANK M. PIERCE and WILLIAM BURGESS PIERCE, citizens of the United States, residing at Chicago, in the county of Cook and State of Illinois, have invented new and useful Improvements in Machines for Wrapping Commercial Coils of Wire, of which the following is a full, clear, and exact description.

10 Our invention relates to machines for wrapping commercial coils of wire by means of ribbons of paper or other suitable material threaded through and wrapped around and around the coils of the same, spirally from the inner to the outer circumference.

15 The object of our invention is to accomplish this wrapping by means of a ribbon the exposed edge of which is folded under, so as to double the thickness of the paper 20 wound around the coil.

Another important object of our invention is to enable the shuttle, by means of which this wrapping is accomplished, to serve as a magazine for the ribbon used in 25 the wrapping operation and to accomplish the storage of the ribbon therein in such manner that the ribbon may be wound upon and conform to both the concaved and convexed side of a bobbin, and be unwound 30 therefrom the same as if it was unwound from a cylindrical reel or drum. And a further object of said invention is to adapt it to the wrapping of commercial coils of wire of varying diameters and sizes.

35 This we accomplish in a simple and expeditious manner that does not require the employment of expert help, by the means hereinafter fully described, and as particularly pointed out in the claims.

40 In the drawings: Figure 1 is a front elevation of our invention. Fig. 2 is a plan view thereof. Fig. 3 is a longitudinal section through the shuttle of the machine drawn to a slightly larger scale. Fig. 4 is a 45 vertical section taken on line 4—4 Fig. 2. Fig. 5 is a transverse section through the central part of the supporting-frame of the rollers supporting the commercial coil of wire in position to be wrapped. Fig. 6 is a 50 vertical section taken on dotted line 6—6, Fig. 5, looking in the direction indicated by the arrows. Fig. 7 is a perspective view of the bobbin. Fig. 8 is a side view of the displaced segmental section of the shuttle,

through which access is had to its inner circumference, drawn to a slightly larger scale. Fig. 9 is a transverse section of said shuttle, taken on line 9—9, Fig. 3. Fig. 10 is a detail view showing the manner of supporting one end of the lever employed to vertically 55 adjust the supporting device of the coil of wire, while being wrapped. Fig. 11 is a plan view of the folding devices of our invention, removed from the machine and drawn full size. Fig. 12 is a front side edge 60 view of the same. Fig. 13 is a longitudinal central section therethrough. Fig. 14 is a view of the discharge end thereof. Fig. 15 is a perspective view of a short strip of ribbon having one edge folded, as when it 65 leaves the shuttle.

Briefly speaking, our invention enables a commercial coil or circular bundle of wire to be placed upon and slowly revolved by a plurality of rollers, and simultaneously 70 wrapped with a ribbon of paper or suitable material by means of an endless or annular shuttle, which rapidly revolves upon its own axis through the eye of the bundle or coil of wire, and substantially at right angles 75 thereto; which shuttle is so constructed that a segment of it can be temporarily displaced or removed, when it is not in rotation, to permit of the insertion or removal of said coil of wire to or from the machine. The 80 machine embodying our invention for accomplishing this result consists of a suitable rectangular frame, A, comprising legs or uprights at each corner connected by suitable side-rails and cross-bars both at the top 85 and near the floor, substantially as shown 90 in Figs. 1, 2 and 4 of the drawings.

Near the center of length of the back of the machine (the side opposite that into which the uncovered coils or bundles of wire 95 are fed to the same), the upper and lower horizontal rails of the frame are connected by two corresponding guide-columns α , α , and slidingly mounted upon these columns is a carrier-frame B. This carrier consists 100 of two corresponding side-plates whose rear ends are extended upward and are provided with knuckles through which said columns pass, and whose forward ends are suitably connected by a cross-bar. Near their forward and rear ends these side-plates are provided with bearings for the drums C and D, and midway between these drums we con- 105

nect the side-plates of the carrier by a transverse bolster *b*, consisting of a suitable length of steel bar, whose vertically disposed ends are secured to said side-plates, above 5 which said ends are given a compound bend before merging into the horizontal portion of the bolster bridging the space between said side-plates. Over each of said side-plates, brackets *c*, *c*, are secured to the ends 10 of the horizontal portion of the bolster, by means of bolts *c'*, that are tapped through downwardly projecting lugs *c*² embracing the edges of the bolster. The upper part of these brackets is offset slightly toward the 15 transverse center of the carrier, and have vertical journals *d* arising therefrom upon which rollers *E* are loosely mounted. The bundles or coils of wire to be wrapped are seated on rollers *C* and *D*, substantially as 20 shown in the drawings, and the rollers *E*, *E*, bear against the sides of the lower portion of said coil and prevent the lateral displacement thereof.

The journals of rollers *C* and *D* are, at 25 one end, extended beyond their bearings, and are provided with suitable sprocket-wheels *D'* and *C'*, that are connected by a chain *e*, and the journal of the rearward-most roller *D*, opposite its sprocket *D'*, is 30 connected to or made integral with a shaft *F*, that extends a suitable distance, and has upon its end a miter gear *f*, which is actuated by pinion *g* revolvable with but adapted to move vertically on a vertical shaft *G*. 35 The end of shaft *F* nearest shaft *G* is journaled in bearings in the end of a lateral frame *h*, that is secured to and projects from the adjacent side-plate of the carrier near its rear end. At the base of the upright 40 portion of this lateral frame *h* in which the last mentioned bearing is made, it is provided with a horizontal extension *h'*, that is provided with a vertical opening through which shaft *G* passes, and which serves to 45 hold pinion *g* in engagement with the gear *f*. This manner of keeping pinion *g* in engagement with gear *f* is made necessary because of the vertical adjustability of the carrier *B*. We accomplish this adjustability 50 by means of a horizontally disposed lever *H*, which latter is fulcrumed at the end of the machine farthest from vertical shaft *G*, and at about its center of length is connected to the underside of said carrier, *B*, by 55 means of vertically disposed links *j*. The end of lever *H* opposite its fulcrum extends beyond the opposite end of the supporting-frame of the machine, and, at a point between the adjacent legs thereof, it has a bolt, 60 *I*, extended transversely through it, whose screw-threaded end enters and is secured in a clamping-ring *J*, which latter surrounds and is adjustable vertically upon a vertically disposed guide-rod *K*, whose upper and lower 65 ends are secured in cross-bars connecting

said legs. Lever *H* is held out from ring *J* by means of a leaf-spring *k*, one end of which bears against the guide-rod *K* and the other against said lever. Bolt *I*, between the lever *H* and its head, is surrounded by an expansion-spring *m*, that prevents said lever from slipping outward too far away from ring *J*, which latter, at a point diametrically opposite that tapped by bolt, *I*, is provided with a handle *n* that assists in vertically adjusting the adjacent end of said lever. The opening of ring *J* is slightly greater than the diameter of the guide-rod *K*, and when the hold is released from said lever its weight will tip the ring so that 70 the latter bites and clamps the rod *K* and holds the lever stationary. When it is desired to raise or lower the adjacent end of said lever, this is done by grasping the lever and handle *n* and moving the ring up and 75 down on rod *K*, as desired. The opposite fulcrumed end of lever *H* can also be adjusted vertically, if desired. This we accomplish by mounting the sleeve *M*, from 80 which the stud forming the fulcrum of said lever projects, upon a vertical guide-rod *N*, and securing said sleeve at any point upon said guide-rod by means of a set-screw *O* tapped through said sleeve and biting into 85 said rod.

The upper end of vertical shaft *G* passes through bearings in the ends of an arm *o* made integral with and projecting from bearings *P* for the drive-shaft *Q* of the machine, and shaft *G* terminates just above 90 this bearing, and is provided with a beveled gear *r* that engages and is driven by a beveled pinion *p* on said drive-shaft. This drive-shaft is, preferably, driven through the medium of a pulley *q* on its rear end, 95 and said shaft extends to and has its forward end journaled in bearings *q'* secured to and projecting from the adjacent forward leg of the supporting-frame of the machine. About midway its length the 100 drive-shaft has a channeled wheel *R* mounted thereon the circumference of whose rear flange *s* is provided with gear teeth. In the same horizontal plane as wheel *R* at the opposite end of the machine, and an 105 equal distance from the vertical plane intersecting the center of length of rollers *C* and *D*, there is another channeled wheel *S*, corresponding in diameter and dimensions to wheel *R*, and this wheel *S* also has its 110 rear flange *t* provided with gear teeth, and is securely mounted upon an idle-shaft *T*, and said idle shaft has its ends journaled in suitable bearings secured to and projecting from the adjacent legs of the machine. 115

The annular shuttle for wrapping the bundle of coiled wire, is seated in the circumferential channels of the wheels *R* and *S* and is revolved thereby, but in order to 120 125 130 135 140 145 150 155 160 165 170 175 180

prevent the bundle or coil of wire from moving laterally while being wound, we have provided vertically disposed rollers U, whose inclined axes have their ends journaled in lugs v of a frame V, which latter is mounted on the lower end of hangers w, that depend from laterally adjustable plates W secured to the forward surface of the upper rail of the rear part of the frame-work of the machine. Said rollers are adjustable toward or from the sides of the bundle or coil of wire by means of horizontal transverse rods x, x, whose contiguous downwardly curved elastic ends press the frames V carrying said rollers toward said bundle of coiled wire and whose opposite screw-threaded ends are tapped through the lugs of a U-shaped frame X, attached to the rear legs of the frame-work of the machine, in which they are adjusted longitudinally by means of nuts y.

The shuttle hereinbefore referred to comprises an annulus or ring of greater diameter than the channeled wheels R and S, in which its periphery is seated, and it has a tubular bobbin-section 2 that takes up about three hundred degrees of its length; it is substantially rectangular in cross-section, and has the space between the ends of said bobbin-section bridged by a portion that can be displaced to permit of a segment of the coiled bundle of wire being inserted within its inner circumference. As shown in the drawings, this displaceable portion 35 of the shuttle consists of two corresponding gates 3, 3, each of which correspond in length to one-half the length of the space to be bridged, and are hinged to the sides of the ends of the bobbin-section, at points between the inner and outer circumference of the bobbin-section, to permit the engaging edges thereof to meet in a longitudinal plane intersecting the axis of the shuttle. These gates have their inner sides curved so as to be concave, when closed, to the curve of the inner circumference of the shuttle, and are secured together by a latch 4, secured to one side thereof, as shown in Fig. 8, and their outer sides are cut away so as to permit them 50 to drop into the position shown in dotted lines in Fig. 8 of the drawings, when the coil or bundle of wire is inserted therethrough. The sides of the shuttle are provided with concentric circular tracks 5 that 55 are adapted to rest upon the circumferential edges of the flanges of wheels R and S, and the rearmost circular track thereof is provided with a series of teeth that engage the teeth of the rear flange of wheel R and the rear flange t of wheel S; thus insuring the positive transmission of the motion of wheel R to the shuttle, and through the latter to wheel S. The sides of gates 3, 3, are provided with projecting portions, 6, that form 65 continuations of tracks, 5, when the gates

are closed, and, if desired these projecting portions may extend beyond the pivots of the gate and have their end edges beveled, so as to engage the end edges of the tracks on the sides of the bobbin-section, and limit the inward movement of the gates when they are closed.

We prefer to make the outer circumferential side of the bobbin section of a removable flexible strap, 7, the end edges of which are provided with hooks 8 and 9, that project beyond said ends and catch in suitable openings in the metal outer circumference 10 of the ends of said bobbin-section. The ribbon, 13, of paper or other suitable material, that is inserted in the chamber inclosed within the walls of the bobbin-section, may be zig-zagged back and forth (not shown), but we prefer to take a ribbon that has been wound upon a drum or cylinder, and make it surround the segmental bobbin, shown in Fig. 7 of the drawings, in the manner shown in Fig. 3 of the drawings, in which said ribbon is made to conform to the convex and concave side of the bobbin, in such a way as to store the greatest amount of ribbon in the most compact and smallest space possible. This bobbin consists of a segmental ladder-shaped frame, which is divided about its center of length, into two corresponding sections 14, 14, comprising segmental side-rails that are connected by cross-bars at suitable points along their length, and by rollers 15, 15 whose diameters exceed the width of the side-rails, and which are, preferably, located equal distances apart. Each of these sections is, preferably, provided with trunnions 16, 16, that consist of cylindrical spindles arranged in alining pairs, and having collars, 17, secured thereto, that limit their outward movement. The inner ends of these spindles are surrounded by a sleeve 18, whose length is less than the distance between the rails of the bobbin, and this sleeve and the exposed part of the inner portions of said spindles, are surrounded with a coil expansion-spring 19, whose ends press outward against the collars 17 of the spindles of said trunnions. This construction is adopted so that the trunnions may be compressed toward each other when the bobbin is inserted in the shuttle-section 2, and when the bobbin is in proper position will automatically spread apart and enter openings 20 in the sides of said section 2, about midway between the inner and outer circumferences thereof.

The bobbin is of such length that when in position within bobbin-section, 2, of the shuttle, one end thereof will come nearer the gate 3 than the other, and it is from this last mentioned end of said section 2 that the ribbon is paid out. In order to provide the most convenient construction of the exit end of the bobbin-chamber, for this purpose,

we prefer to close the adjacent end of the same by a transverse partition 21, and to make an opening 22 in the inner circumference of said chamber, near said partition, out through which the ribbon is drawn from the concaved side of the bobbin. In order to facilitate the bodily movement of the ribbon around the bobbin (which is immovable with the bobbin-chamber), we provide said chamber with a series of transverse rollers 23, that are journaled in bearings in the sides of the bobbin-section adjacent to the inner circumference thereof. After passing out of the opening 22, the ribbon passes between leaf-spring 25 and said partition to prevent its paying out too rapidly;—said spring 25 being secured at its opposite end to a suitable transverse member 26, and having its pressure against the ribbon regulated by means of an adjusting-screw 27. After passing between tension spring 25 and partition 21, the ribbon passes over the outer pivoted end of a tongue 30, which consists of a flat strip of less width than the ribbon, and having its outer portion curved to form a shoulder. The position of this tongue while performing most of its work is inclined from its outer pivoted end to its inner free end, although the latter is free to move so as to accommodate the tongue to the angle assumed by the ribbon as it is wrapped around the coil. The longitudinal edge 35 of this tongue nearest the rear of the machine is flanged toward the outer circumference of the shuttle, and near its free end this flange projects farther and is then bent horizontally over the end of the tongue to form an overhang bracket 36. Secured to this bracket by any suitable means is a plate 32, which is parallel to and opposes the outer flat surface of the free end of the tongue, and coöperates therewith to fold one longitudinal edge of the ribbon. In order to accomplish this folding, the width of the companion plate, 32, is made greater than that tongue, and its longitudinal edge 33 nearest the front of the machine, is bent under the corresponding edge of the tongue, thus forming a passage that finishes the fold of the forward edge of the ribbon while in transit between said plates. The commencement of the fold for the edge of the ribbon is made when the ribbon is moving over the curved shoulder at the pivoted end of the tongue. This as shown in Figs. 11 and 12 of the drawings, starts the fold in an easy manner, and permits the ribbon to run easily and rapidly through the folding devices without undue resistance to the pull of the ribbon caused by its wrapping around the coil of wire.

In operation when the coil or bundle of wire has been placed in position, and the shuttle arranged at right angles thereto, and placed, so that as it revolves it will revolve

through the eye of the said coil, power is imparted to the machine, and, while the said coil of wire revolves slowly, the shuttle will revolve rapidly and wrap said ribbon with its forward edge folded under, around and 70 around said coil, from the inner circumference to the outer circumference thereof, the entire endless length of the coil, whereupon the machine is stopped; the ribbon cut off and the end thereof tucked under one of the 75 bights thereof to prevent it from unwinding. The gates of the shuttle are then opened and the wrapped coil removed, and then an uncovered coil or bundle is inserted in place in the machine; the gates of the shuttle are 80 closed and locked, and the wrapping of the last inserted coil proceeds as hereinbefore stated. In the operation of the machine thus briefly explained the parts thereof operate and perform the functions hereinbefore fully explained. In order to support the shuttle when the displaced portion thereof is lowermost, and to steady it while in motion, we prefer to provide the rear surface of tracks 5 of the shuttle with a rearwardly projecting concentric flange, and in the longitudinal vertical plane of the axis of the shuttle provide an upper and lower idle wheel 37 and 38, that, respectively, engage the inner and outer circumference of 90 said track flange. If desired, the upper wheel 37, may have a stepped portion of less diameter on its forward side that may engage the crowns of the gear teeth of said flange, 5. These idlers, 37 and 38, are journaled on suitable studs, secured to and projecting from the vertically disposed end of a bracket 39, secured to and projecting from the center of length of the rear upper rail of the supporting frame of the machine. 100

It will, of course, be obvious, that our improved machine may be used to wrap similar shaped bundles of other material than wire. We wish to be understood as contemplating the use of our machine for all such purposes, and although the description of our invention has herein specifically referred to coils of wire, we desire to comprehend its application to all purposes to which its functions adapt it. 110

What we claim as new is:—

1. In a wrapping machine of the class described, a frame, revoluble channelled supporting wheels mounted thereon, a shuttle revoluble with said wheels and seated in the channels thereof, rollers at the upper end of the frame engaging a portion of said shuttle partially to support the same, and adjustable means for supporting and rotating an article to be wrapped. 120

2. In a wrapping machine of the class described, a frame, a carriage adjustable vertically therein, driving and supporting means on said carriage for an article to be wrapped, a lever pivoted on said frame and connected 130

- to said carriage to adjust and maintain the same in various adjusted positions, a shuttle adapted to apply wrapping material to a body being wrapped, and means supporting 5 said shuttle and adapted to drive the same.
3. In a wrapping machine of the class described, a frame, a carriage movable vertically therein, driving means mounted on said carriage adapted to support and rotate 10 an article to be wrapped, a lever having a movable fulcrum point adapted to adjust said carriage in said frame, a shuttle revolvable through the eye of a body being wrapped to apply wrapping material thereon, and rev- 15 oluble supporting wheels having channels therein in which said shuttle is seated, and to one of which said shuttle is geared for rotation thereby.
4. In a wrapping machine of the class de- 20 scribed, a frame, channeled rollers mounted thereon, gear teeth formed on said rollers within said channels, a revolute annular shuttle supported on said rollers and engag- 25 ing in the channels thereof, a geared rim on said shuttle meshing with the teeth of said rollers, a drive for one of said rollers to drive said shuttle, a pair of rollers mounted at the upper end of the machine engaging a 30 portion of the shuttle to assist in supporting the same, and vertically adjustable driving and supporting means for an article to be wrapped.
5. In a device of the class described, a frame, channeled rollers mounted on each 35 side thereof at the upper end thereof, a revolute annular shuttle supported in and engag- 40 ing in the channels of said rollers, a geared rim on said shuttle, rollers mounted on said frame at the upper end thereof en-
- gaging above and beneath said rim on said 45 shuttle to support the same, a carriage vertically adjustable in the frame, and means thereon to support and rotate an article to be wrapped.
6. In a device of the class described, a frame, vertical rods mounted therein, a carriage 50 slideable thereon, a vertically disposed driving shaft, a gear feathered thereon and supported by and movable with said carriage, a shaft journaled in said carriage, a 55 gear thereon meshing with said first-mentioned gear, rollers mounted in said carriage and connected to be driven by said shaft to support and rotate an article for wrapping, and a shuttle revolvably mounted to apply 60 wrapping material on the article.
7. In a device of the class described, a frame, a carriage movable vertically therein, a lever having a movable fulcrum point connected to said carriage to adjust the same 65 vertically in said frame, means maintaining said lever in different positions with respect to said frame, channeled rollers mounted at the upper end of said frame, gear teeth forming a part thereof, a shuttle engaging 70 in the channels of said rollers and supported thereby, a geared rim on said shuttle meshing with the toothed portions of said rollers, and a section removable from said shuttle to permit insertion therethrough of an article 75 to be wrapped supported upon said carriage.

In witness whereof we have hereunto set our hands this 18th day of May, A. D., 1909.
